CARRIER FOR ROPE, WIRE, AND THE LIKE

Fred W. Zink, Detroit, Mich., assignor to Whitehead Stamping Company, Detroit, Mich., a corporation of Michigan

Application December 27, 1937, Serial No. 181,959

7 Claims. (Cl. 242—96)

This invention relates generally to portable carriers for rope, wire and the like and refers more particularly to a hand reel.

One of the essential objects of the invention 5 is to provide a strong and durable reel that is light in weight and can be manufactured at a comparatively low cost.

Another object is to provide a reel that, aside 10 from the handle mounting, can be quickly and accurately made from sheet metal stampings.

Another object is to provide a reel wherein 15 two stampings cooperating with each other to form the body and rope-receiving portions of the device are constructed and arranged in such 5 a way that they also form suitable bearings for the handle mounting.

Another object is to provide a reel wherein 20 portions of the cooperating stampings, preferably at the juncture of the rope-receiving portions with the body, are offset or spaced apart to provide in effect notches which may be alternately used as desired for receiving the knotted end of a rope when the latter is initially applied to the reel.

Other objects, advantages and novel details of 25 construction of this invention will be made more apparent as this description proceeds, especially when considered in connection with the accompanying drawing, wherein:

Figure 1 is an elevation of a reel embodying 30 my invention and showing rope applied thereto;

Figure 2 is a view similar to Figure 1 without the rope being applied;

Figure 3 is an end elevation of the reel;

Figure 4 is a top plan view of the reel;

Figure 5 is a vertical sectional view taken substantially on the line 5—5 of Figure 2.

Referring now to the drawing, A is the body, B and C, respectively, are the rope-receiving 40 portions, and D is the handle mounting of a reel embodying my invention. Preferably the body A and rope-receiving portions B and C are formed from two sheet metal stampings 1 and 2, respectively, which, as shown, are outwardly opening channels having closed rounded ends 3.

The body A is preferably oval-shaped and is formed by oppositely-bowed intermediate portions 4 and 5, respectively, of the stampings, while the rope-receiving portions B and C are 45 substantially U-shape in configuration and are formed by oppositely-curved end portions 6 and 7, respectively, of the stampings. At the juncture of the body A and rope-receiving portions B and C, the stampings 1 and 2 have abutting 50 substantially flat portions 8 and 9 that are se-

cured rigidly together by rivets 10. To permit the knotted end of a rope such as 11 to be anchored at either end of the device, the flat portions 8 and 9 are offset slightly at the inner ends of the curved portions 6 and 7 to provide recesses 12 and 13, respectively, which simulate notches for the reception of said knotted end of the rope.

A handle 14 is sleeved upon a shaft 15 that extends freely through aligned openings 16 and 17, respectively, in the bowed intermediate portions 4 and 5 forming the body of the reel. Preferably this shaft 15 is provided at its lower end below the handle 14 with a head 18 and is provided at its opposite end above the base 19 of the upper stamping with a head 20. The handle 14 is substantially equal in length to the distance between the lower head 18 and the base 21 of the lower stamping, hence the parts are so constructed and arranged that the shaft 15 will be held against longitudinal movement in the 20 openings 16 and 17, and the handle 14 will likewise be prevented from movement longitudinally of the shaft, but the stampings 1 and 2 as a unit are free to rotate about said shaft on said handle.

What I claim as my invention is:

1. A reel having two stampings providing an elongated body and rope-receiving portions at opposite ends of said body, said stampings being provided at the juncture of said body and one of said rope-receiving portions with offset portions cooperating with each other to provide a recess for the reception of the knotted end of a rope.

2. A reel having an oval-shaped body and provided at opposite ends of said body with substantially U-shaped rope-receiving portions, the body and rope-receiving portions being formed from two outwardly opening channels, the bases of said channels at the juncture of the U-shaped rope-receiving portions and body being substantially flat and rigidly secured together, said flat portions being provided at the bases of the U-shaped portions with cooperating offset parts forming notches for the reception of a knotted end of the rope, a shaft extending freely through aligned openings in the bowed sides of the body at the center thereof, and a handle sleeved on said shaft at one side of the body, opposite ends of the shaft being headed, and the construction and arrangement being such that the shaft is held against longitudinal movement in the body, the handle is held against longitudinal movement on the shaft, and the body is free to rotate about the shaft on said handle.

3. A reel having an elongated body and pro-

vided at opposite ends of said body with substantially U-shaped rope-receiving portions, the body and rope-receiving portions being formed from two outwardly opening channels, the bases of 5 said channels at the juncture of the U-shaped rope-receiving portions and body being substantially flat and rigidly secured together, a shaft extending freely through aligned openings in the body at the center thereof, and a handle 10 sleeved on said shaft at one side of the body.

4. A reel having a substantially oval-shaped body, and substantially U-shaped rope-receiving members opening outwardly from opposite ends of said body, said body and members being formed 15 from two outwardly opening channels, the bases of said channels at the juncture of the members and body being face to face and rigidly secured together, opposite bowed sides of said oval-shaped body being provided substantially midway their 20 ends with substantially aligned holes, and a handle shaft engaging said holes.

5. A reel having an elongated body and provided at opposite ends of said body with substantially U-shaped rope-receiving portions, the body and rope-receiving portions being formed from two outwardly opening channels, the bases of 25 said channels at the juncture of the U-shaped rope-receiving portions and body being substantially flat and rigidly secured together, said flat portions being provided at the bases of the U-shaped portions with cooperating offset parts 30

forming notches for the reception of a knotted end of the rope, a shaft extending freely through aligned openings in the bowed sides of the body at the center thereof, and a handle sleeved on said shaft at one side of said body. 5

6. A reel having an elongated body and provided at opposite ends of said body with substantially U-shaped rope-receiving portions, the body and rope-receiving portions being formed from two outwardly opening channels, the bases 10 of said channels at the juncture of the U-shaped rope-receiving portions and body being substantially flat and rigidly secured together, said flat portions being provided at the bases of the U-shaped portions with cooperating offset parts 15 forming notches for the reception of a knotted end of the rope, and a handle shaft spanning the space between and connected to opposite sides of said elongated body.

7. A reel having an elongated body and provided at opposite ends of said body with substantially U-shaped rope-receiving portions, the body and rope-receiving portions being formed from two outwardly opening channels, the bases 20 of said channels at the juncture of the U-shaped rope-receiving portions and body being substantially flat and rigidly secured together, and a handle shaft spanning the space between and connected to opposite sides of said elongated body. 25
